UNITED STATES PATENT OFFICE.

ANTIME MOTTEAU, OF BUENOS AIRES, ARGENTINA.

METALLIC FRAME FOR WINDOWS AND THE LIKE.

1,367,418.

Specification of Letters Patent.

Patented Feb. 1, 1921.

Application filed February 14, 1919. Serial No. 276,983.

To all whom it may concern:

Be it known that I, ANTIME MOTTEAU, a citizen of the French Republic, residing at No. 1272 Garay street, Buenos Aires, Argentina, have invented certain new and useful Improvements in Metallic Frames for Windows and the like, of which the following is a specification.

This invention relates to a new system of metallic construction for the frames of house windows and the like.

In the construction of window frames and the like and other similar metal joinery of reticular character the pane is required to fit throughout its four edges upon the rims of the frame. For this purpose it is necessary that the T frames which form the said structure shall fit into each other so that the beadings of the T frames may all remain in the same plane. These frames have hitherto been made of grooved iron, a construction which diminishes the strength of the structure causing breakages a loss of tightness and leakages in the joints between the window panes and the frames.

In order to avoid these drawbacks it has been attempted, for instance, to make the frames of cast steel or iron, but this method is exceedingly expensive.

The present invention does away with these difficulties and makes it possible to obtain a reticular metal structure, the strength of which is not impaired through joinings, groovings or cuttings in the metal.

In order that the invention may be clearly understood and easily carried into practice I show in the accompanying drawings several embodiments of the same, as follows:

Figure 1 is a plan view of a complete reticular construction.

Fig. 2 is an enlarged view of part of a framing, showing the connections between the several parts which compose it.

Fig. 3 is a section on line A—B of Fig. 2.

Fig. 4 is a section on line C—D of the said Fig. 2.

Fig. 5 is a perspective view of one end of the cross bar of Fig. 4.

Fig. 6 is a section on line E—F of Fig. 2, showing a cross bar of T-section.

Fig. 7 is a side elevation of one of the cross-pieces of the joint.

Fig. 8 is a perspective view of the end of the said cross-piece.

Fig. 9 shows the application of the joint in the case of a bar or cross-piece of L-section.

Fig. 10 shows the invention as applied to the joint between T-irons.

Fig. 11 shows a metallic carpenter's shutter made according to my invention.

Fig. 12 is an enlarged section on line A'—B' of one of the cross bars of Fig. 11.

Fig. 13 is an enlarged section of the joining G of the said Fig. 11.

Fig. 14 is an enlarged view on line E'—F' of Fig. 11.

And finally, Figs. 15 and 16 are respectively a perspective view and a section of certain constructions combined with the joining according to the present invention enabling the window panes to be held in position in the framings.

Referring first to the construction illustrated in Figs. 1 to 10 inclusive, 1 indicates the main or outer bars which form the frame of a reticular structure and which may have any desired cross-sectional shape. The crossbars 2 shown in Figs. 3, 4 and 5 are of X-section, are formed without slots or grooves of any kind and extend from one end to the other of the frame 1, parallel to each other and uniformly spaced, so that their horizontal webs may form the reticular frames for the window panes. The union of the aforesaid crossbars with the irons 1 of the frame takes place as illustrated in Figs. 2, 3 and 5 that is, with the ends of the irons 2 so constructed that each forms a kind of socket which fits over the horizontal web of the adjacent frame bar 1.

The horizontal web 3 of the cross-bar 2 has each end offset downwardly and forwardly at 4 in such a way as to provide a gap or socket between said end and the adjacent end of the upper vertical web 7 of the cross bar, and this gap or socket receives in it the horizontal web 6 of the frame bar 1 which is secured to the offset end 4 by means of the rivets 5. The upper webs 7 of the cross bars 2 terminate in tongues 90 which fit in slots in the frame bars 1 and are secured therein.

The lower web 8 is integrally connected to the horizontal web as shown in the above figures and is disposed co-planar with the upper web 7.

Having thus constructed the frame and the crossbars I can then proceed to the set-

ting up of the reticulation. To this end cross-pieces 9 are required of **T** or **X**-section according to the strains to be supported, which have vertical webs of the same height 5 as those of the cross bars 2.

The joints between the crossbars 2 and the cross-pieces 9 are effected by means of gaps or sockets formed in the same manner as those used for the connection of the cross-bars with the frame bars 1. It is, however, advisable that the webs 3 shall all meet at the same height both in the frame and in the crossbars and cross-pieces in order to facilitate the formation of the joints, with 10 the result that each of the reticulations thus formed is composed of **T** or **X**-irons, the horizontal webs whereof are in the same plane and form the seat upon which the glass pane is supported.

20 From the above it will be clearly understood that the resistance of the frames corresponds to the maximum strength of the sections of the respective irons employed, instead of being reduced to about one half, as is the case with the frames 25 formed in the manner used heretofore.

In Figs. 6 to 8 a construction is shown wherein the bars 2 are of **T** section. These bars may also be conveniently used for 30 forming the cross-pieces 9, in which case the joining sockets have the form illustrated in Figs. 7 and 8, from which it will be evident that bars or cross-pieces of **X**-sections, as used in Figs. 4 and 5, may also be employed 35 with these bars.

The same connection may also be used in the case where **L**-iron is employed (Fig. 9) or **T**-irons of double strength. These 40 connections may be applied between the cross-bars and the frame bars as well as between the cross-pieces and the frame bars.

In Figs. 11 to 14 inclusive, there is illustrated an embodiment of this invention as applied to metallic joiner work. A foot-piece 10 is provided in order to afford a 45 suitable support for the framing. This framing includes as in the foregoing cases, an iron frame 1 of **T**-sections, and in which there are fixed by means of the above described joints the free ends of the bars 2 and the cross pieces 9, said cross pieces being fixed upon the bars in the same manner as above.

50 In the said figures, and in the subsequent ones, similar characters of reference refer to the same or like parts as those of Figs. 1 to 10.

The glass panes, which in this case are 55 transparent, are supported in the manner usual in metallic joiner work. As shown in Fig. 12, the panes 11 are supported upon the lateral or horizontal webs 3 of the cross bars 2 by means of a molding 12, which serves to hold the panes against the said 60 webs.

The connection of the glass work with the window frame and with the support is effected in a manner similar to that already described. In this case, an **X**-section bar, is substituted for the cross-bar, one of the two lateral webs 3 of the section bar serving to support the glass 11, and the other to engage with the support 10, as illustrated in Fig. 14. The fixing of the pane 11 and of the part 10 may be effected by means of the 70 moldings 12 or in any other suitable manner. In Figs. 15 and 16 a special arrangement is shown which permits of easily inserting the panes in their frames upon the webs of the cross pieces and frame bars. 75 The arrangement includes a metallic plate or cap 13 which is introduced between the web 6 of the frame bar and the ends of the web 7 of the cross bar and by which once the connection between both bars has been 80 made in the manner described, the glass pane remains held between them. In this way once the glass pane is placed in position in the frame, the free ends of the plates or covers which remain attached by their 85 four corners, are bent over against the surface of the said glass pane and hold it fixedly in position.

Having now fully described and ascertained the nature of my present invention 90 and in what manner the same is to be performed, I declare that what I claim is:

1. A reticulate metallic structure of the character indicated, comprising a framework which consists of a pair of end frame bars; cross-bars connecting said frame bars and arranged in spaced, parallel relation to one another; and short length cross-pieces arranged between and at right angles to the cross-bars and connected to the same at opposite ends, each of the several bars and cross-pieces having at least one horizontal and one vertical longitudinal web which is co-extensive therewith: the horizontal web of each cross-bar and cross-piece having its ends offset downwardly and forwardly to form a socket between such offset end and the adjacent end of the vertical web of the respective bar or cross-piece; each socket receiving and having secured therin the opposite portion of the horizontal web of the adjacent frame bar.

2. A reticulate metallic structure of the character indicated, comprising a framework which consists of a pair of end frame bars; cross-bars connecting said frame bars and arranged in spaced, parallel relation to one another; and short length cross-pieces arranged between and at right angles to the cross-bars and connected to the same at opposite ends, each of the several bars and cross-pieces having at least one horizontal and one vertical longitudinal web which is co-extensive therewith; the horizontal web of each cross-bar and cross-piece having its 110 115 120 125 130

ends offset downwardly and forwardly to form a socket between such offset end and the adjacent end of the vertical web of the respective bar or cross-piece; each socket receiving and having secured therein the opposite portion of the horizontal web of the adjacent frame bar; each cross-bar being provided at the opposite ends of its vertical web with projecting terminals

which engage in slots formed in the opposite portion of the vertical web of the adjacent frame bar. 10

In testimony whereof I affix my signature in the presence of two witnesses.

ANTIME MOTTEAU.
